UNITED STATES PATENT OFFICE.

IRA NAYLOR AND JAMES C. TUCKER, OF BRAXTON, WEST VIRGINIA.

RAIL-JOINT CLOSER.

1,390,153.

Specification of Letters Patent. Patented Sept. 6, 1921.

Application filed January 31, 1921. Serial No. 441,379.

To all whom it may concern:

Be it known that we, IRA NAYLOR and JAMES C. TUCKER, citizens of the United States, residing at Braxton, in the county of 5 Braxton and State of West Virginia, have invented new and useful Improvements in Rail-Joint Closers, of which the following is a specification.

This invention relates to railway devices, 10 particularly to device for lining up rails which have become displaced and has for its object the provision of a novel device of this character including members engageable with rails at the opposite sides of a joint and 15 operable to draw the rails together endwise which will not only take up or close an excessive space at the joint but which will also line up the rails so that they will have the proper gage, this device being particularly 20 adapted for use in connection with comparatively light rails such as are used for mine cars and the like and being a distinct improvement over the well known practice of hammering the ends of the rails to force 25 them into place or inserting wooden filler blocks.

An important object is the provision of a device of this character which includes rail gripping members secured to the rails and 30 connected by screw means for drawing the members and consequently the rails together.

An additional object is the provision of a device of this character which will be simple and inexpensive in manufacture, highly 35 efficient in use, positive in action, durable in service, and a general improvement in the art.

With the above and other objects and advantages in view, the invention consists in 40 the details of construction to be hereinafter more fully described and claimed and illustrated in the accompanying drawings in which—

Figure 1 is a side elevation of our device 45 engaged upon rails,

Fig. 2 is a plan view,

Fig. 3 is an end view,

Fig. 4 is a cross sectional view, and

Fig. 5 is a bottom plan view of one of the 50 rail grips.

Referring more particularly to the drawings, the letters A and B designate the ends of rails to be set and these rails have their webs provided adjacent their ends with the 55 usual holes C, for the passage of the bolts which hold the fish plates. In carrying out

our invention we provide two members designated broadly by the numerals 9 and 10 and associated with the rails A and B, respectively. The member 9 is formed as a 60 plate 11 designed to be placed over the top of the rail A and including depending side portions 12 which are slotted, as shown at 65 13, for the reception of pivoted jaws 14 engageable with the web of the rail and normally urged into such engagement by leaf-springs 15. The end portions of the jaws 14 are formed with transverse holes 16 designed to be brought into registration with one of the holes C, subsequently to which a bolt 17 70 is passed through the holes whereby the member 9 will be firmly anchored to the rail.

The member 10 likewise comprises a plate 18 formed upon its underside with side portions 19 extending at the sides of the rail B. 75 This member 10 is provided with jaws 20 identical with the jaws 14 and urged into engagement with the rail by springs 21 and secured to the rail by the bolt 22.

Formed or secured upon the top of the 80 member 9 is an upstanding ear 23 having a smooth bore 24 through which is shiftably engaged the smooth end 25 of an elongated screw rod 26 which has its opposite end squared, as shown at 27, for engagement by 85 a wrench or the like. Mounted upon the top of the plate 18 is a split nut structure including a lower portion 28 and the upper hinged portion 29. The portion 28 carries ears 30 adapted to coöperate with a lug 31 on the 90 portion 29, and 32 designates a wedge key designed to be driven through holes in the ears 30 to engage over the lug 31 for locking the sections of the split nut together. It is preferable that this key or wedge be 95 connected with the member 10 by means of a flexible chain or the like 33. It is of course apparent that the screw 26 passes through the split nut member.

In the operation of the device it will be 100 seen that the members 9 and 10 are engaged upon the rails A and B, respectively, as above described, with the screw 26 in position. When the screw is rotated it will be seen that the member 10 will be drawn toward the member 9, or vice versa, depending upon which rail is positively anchored to its ties. By means of this action and resultant movement it will be seen that rails which have become displaced may be 110 pulled longitudinally to decrease an excessive gap between them, this movement fur-

thermore bringing the rails into proper alignment in case they have become spread. It is to be noted that the device entirely eliminates any necessity for hammering the 5 rails and consequently damaging them, as is one of the ordinary practices in present use.

While we have shown and described the preferred embodiment of our invention, it 10 is of course to be understood that we reserve the right to make such changes in the form, construction, and arrangement of parts as will not depart from the spirit of the invention or the scope of the subjoined 15 claims.

Having thus described our invention, we claim:

1. A device of the character described comprising a pair of members designed to 20 be secured upon the end portions of meeting rails, a bracket on each member, one bracket being formed with a smooth bore and the other being formed with a split nut capable of being opened, and a screw 25 having one end revolvably engaged through said smooth bore and having its other end portion threadedly engaged within said split nut.
2. A device of the character described comprising a pair of members adapted to 30 be secured upon the end portions of meeting rails, a bracket formed on one of said members and having a smooth bore, a bracket on the other member having a 35 threaded bore, a screw having one end revoluble within said smooth bore and having its other end threaded within said threaded bore, and pivoted spring-pressed rail gripping jaws carried by said members.
3. A device of the character described 40 comprising a pair of members designed to

be engaged upon the end portions of meeting rails and each including a plate disposable upon the top of a rail and having depending side portions engaging the web 45 of the rail, bolts carried by said members and adapted to pass through the fish plate bolt receiving holes of the rails, and means for moving said members toward each other relatively comprising a bracket member, one 50 member having a smooth bore, a split nut swiveled upon the other member and having a threaded bore, and a screw rotatably engaged within said first named bore and having threaded engagement within said 55 threaded bore.

4. A device of the character described comprising a pair of members designed to be engaged upon meeting rails near the end portions thereof and each including a 60 body formed as a plate portion having depending side portions disposed at opposite sides of the associated rail, a pair of horizontally movable jaws carried by each member and spring-pressed into engagement 65 with the web of the associated rail, the end portions of said jaws being formed with holes for the passage of securing bolts designed to pass through the fish plate bolt receiving holes of the webs, a member on 70 the top of one of said plate portions having a smooth bore, a split nut member mounted upon the other of said members and provided with means whereby the sections thereof may be locked together, and a screw 75 rotatable through said extension and having a threaded portion engaged within said split nut member.

In testimony whereof we affix our signatures.

IRA NAYLOR.
JAMES C. TUCKER.
